CLAIM

The ornamental design for the lamp, as shown and described.

DESCRIPTION

1. Lamp

2. Lamp

Fig. 1.1 is a perspective view of the lamp showing a first embodiment of the new design;

Fig. 1.2 is a left view thereof;

Fig. 1.3 is a right view thereof;

Fig. 1.4 is a front view thereof;

Fig. 1.5 is a rear view thereof;

Fig. 1.6 is a top view thereof; and

Fig. 1.7 is a bottom view thereof.

Fig. 2.1 is a perspective view of the lamp showing a second embodiment of the new design;

Fig. 2.2 is a left view thereof;

Fig. 2.3 is a right view thereof;

Fig. 2.4 is a front view thereof;

Fig. 2.5 is a rear view thereof;

Fig. 2.6 is a top view thereof; and

Fig. 2.7 is a bottom view thereof.

(Continued)

The broken lines on the drawings depict portions of the lamp that form no part of the claimed design.
